UNITED STATES PATENT OFFICE.

AARON SIMONS, OF NEW YORK, N. Y., ASSIGNOR OF ONE-FOURTH TO NATHAN WEINBERG AND ONE-FOURTH TO ISSAY WEINBERG, BOTH OF BROOKLYN, NEW YORK.

FOWL-PLUCKING DEVICE.

Application filed February 12, 1926. Serial No. 87,733.

This invention is an improvement in fowl plucking devices, and relates more particularly to the means employed for gripping the feathers, applying the required pulling action, and thereafter releasing them.

As one important feature I provide a hollow rotatable member having an aperture through which the feathers are caused to extend, preferably by suction, and within this is a second member with which the portion of the outer member at the rear edge of the aperture engages at the proper point during the rotation of said member to effect the feather gripping action. As the outer member continues to rotate, the feathers are bent around said edge and the further rotational movement exerts the required pulling action on the feathers gripped between said members.

As a further important feature I make the inner member rotatable about an axis eccentric in respect to the axis of the outer member.

As a further feature, I provide means for rotating the inner member in the opposite direction to that of the rotation of the outer member during the feather gripping action.

As a further important feature I provide a pair of rotatable members within the outer member and in driving relationship to each other, whereby each, when driven rotates the other in the opposite direction.

As another important feature I provide means for controlling the application of the suction pressure to the feathers and the guiding of them into the apertures of the outer rotatable member.

In the accompanying drawings I have illustrated one embodiment of my improved construction, but it will be evident that various changes may be made in the details of construction without departing from the spirit and scope of my invention. I have also illustrated in the drawings one form of apparatus which may be employed for operating my improved plucking mechanism, but obviously other forms of apparatus might be employed.

In the accompanying drawings:

Fig. 1 is a transverse section through the feather gripping and pulling parts, said section being taken on the line 1-1 of Fig. 2.

Fig. 2 is a longitudinal section taken on the line 2-2 of Fig. 1.

Fig. 3 is a side elevation of an apparatus

for supporting and operating my improved plucking mechanism, and

Fig. 4 is an end view of the apparatus shown in Fig. 3.

In the construction illustrated in Figs. 1 and 2, there is provided a rotatable member having circular parallel end walls 10 and a peripheral wall 11. The peripheral wall is subdivided into sections so as to provide a plurality of apertures 12 extending lengthwise of the peripheral wall, and of substantially the full length of the rotatable member. For rotating this member there is provided a drive shaft 13 to which one of the end walls 10 may be keyed or otherwise rigidly secured. The other end wall may be journaled on a non-rotatable part as hereinafter described.

The hollow rotatable member is mounted in a suitable casing having end walls 14 and 15 which are parallel and disposed closely adjacent to the outer sides of the end walls 10 of the rotatable member. The casing also includes an outer or peripheral wall 16 a portion of which may approximately follow the peripheral wall of the rotatable member, but another portion of which may extend approximately tangentially to a conduit 17 leading to suction means. The peripheral wall 16 has a main aperture 18 through which the feathers may extend, and a second aperture 19 spaced therefrom and through which air may enter.

One end wall of the casing, for instance the wall 14, may be rigidly secured to a sleeve, bearing, or frame part 20 within which the driving shaft 13 is mounted. The other end wall serves as a support for the inner rotatable members. As shown, the end wall 15 of the casing has rigidly secured thereto a sleeve 21 which may be in part supported by or may serve as a bearing for the inner end of the shaft 13. This sleeve 21 has two pairs of radially extending lugs or ears 22, the two lugs of each pair being disposed at opposite ends of the sleeve and serving to support a spindle or shaft 23 disposed parallel to the main shaft, but at one side thereof. Mounted upon each spindle 23 is a rotatable member in the form of a roller. This has an inner fibre bushing 24 and an outer wall, layer, or jacket 25 of rubber, rubber composition, or other suitable yielding material. The ears or lugs 22 are so positioned in respect to each other and in

respect to the diameters of the two rollers that the two rollers are in driving relationship to each other, and also frictionally engage the inner surface of the peripheral wall 11 of the hollow rotatable member. The driving connection between the two rollers is preferably by direct frictional engagement of their outer surfaces, so that the two rotate in opposite directions if either is rotated by 10 the outer member.

The aperture 18 of the casing is so positioned as to receive the feathers from the fowl, and one of the two rollers is disposed just inside of this aperture and directly in 15 the path of the feathers. The other inner roller is disposed at the side of the first mentioned roller in the direction of travel of the peripheral wall of the outer member.

In the operation of my improved device 20 the fowl is positioned adjacent to the opening 18 if the mechanism be a part of the stationary machine, or the part 18 is brought to the desired position on the fowl if the device be a hand operated or portable one. 25 The suction applied through the conduit 17 tends to draw the feathers into the casing through the aperture 18, and between the lower roller and the edge 26 of the aperture 18. The hollow member is rotated 30 clockwise so that each wall section 11 in succession will move downwardly and forwardly between the roller and the edge 26. In this way it will enter between certain of the feathers and will grip a portion of them 35 between its front or advancing edge and the under side of the roller. The roller will cause the feathers to fold against the inner surface of the wall 11, as this wall advances, and the roller will be rotated by engagement 40 with the advancing feathers but will hold them firmly until they are pulled out. As the wall 11 advances with the feathers folded around its front edge, it will come to the second roller and will there cause the 45 second roller to rotate in the same direction as the outer member is rotated. At this time the first mentioned roller will be out of engagement with the outer casing so that it is not directly driven by the latter and will 50 be driven by its engagement with the roller shown at the left in Fig. 1. This will cause the lower roller to rotate in the opposite direction and continue this rotation until its engagement with the feathers causes a 55 gripping of the latter and a reversal of the direction of rotation of the roller. The two rollers thus rotate first in one direction and then in the other, and the rotation of the lower roller while gripping rotates the other 60 roller in such a direction as to free the feathers from gripping position after they are pulled out. As soon as they are freed the blast of air in the inlet 19 carries them to the conduit and to the desired point of 65 disposal. The air entering the conduit 18

lifts the feathers away from the skin and holds them up so that the wall 11 may swing beneath them and properly grip them close to the skin. The amount of air entering the aperture 18 may be regulated by a damper 70 or baffle plate 27 which is hinged at the edge 26 and has its free edge movable toward and from the periphery of the outer rotatable member or drum. It will be apparent that each wall section 11 when considered 75 by itself is merely a curved blade rotatable about its approximate center of curvature. The drum merely forms a plurality of such blades.

As previously indicated, the parts shown 80 in Figs. 1 and 2 may be employed in a hand tool or as a part of a stationary machine. In Figs. 3 and 4 I have shown a machine in which there is a standard 30 mounted on a base 31, and serving to support the conduit 85 17 and the frame part or shaft bearing 20. The base 31 may support an electric motor 32 which may be connected by pulleys and a driving belt to the shaft 13. The motor may also drive an electric fan or suction pump 34 90 which is connected to the conduit 17.

Various other mechanisms might be provided for supporting and driving the main operating parts.

Having thus described my invention, what 95 I claim as new and desire to secure by Letters Patent is:—

1. A fowl plucking device including a curved blade rotatable about the approximate center of curvature, and a member 100 adapted to be engaged thereby and disposed between said blade and said center, said member and said blade forming coacting feather gripping and pulling members.

2. A fowl plucking device including a 105 curved blade rotatable about the approximate center of curvature, and a roller disposed between said blade and said center, and adapted to be engaged by said blade during the rotation of the latter.

3. A fowl plucking device including a rotatable drum having its peripheral wall formed of spaced sections with intermediate 115 apertures, and a member disposed between said blade and said center and adapted to engage with said sections in succession for pulling the feathers.

4. A fowl plucking device including a rotatable drum having its peripheral wall formed of spaced sections with intermediate apertures, and a roller disposed between said blade and said center, and adapted to engage with said sections in succession for pulling the feathers.

5. A fowl plucking device including a 125 curved blade rotatable about the approximate center of curvature, a roller disposed between said blade and said center, and adapted to be engaged by said blade during the rotation of the latter, and means for ro- 130

- tating said roller in a direction opposite to the direction of rotation of said blade.
6. A fowl plucking device including a rotatable drum having its peripheral wall formed of spaced sections with intermediate apertures, a roller disposed between said wall and said center, and adapted to engage with said sections in succession for pulling the feathers, and means for rotating said roller in a direction opposite to the direction of rotation of said drum.
7. A fowl plucking device including a curved blade rotatable about the approximate center of curvature, and a pair of rollers disposed between said blade and said center and adapted to be engaged in succession by said blade during the rotation of the latter.
8. A fowl plucking device including a rotatable drum having its peripheral wall formed of spaced sections with intermediate apertures, and a pair of rollers within said drum and adapted to rotate in opposite directions.
- 25 9. A fowl plucking device including a rotatable drum having its peripheral wall formed of spaced sections with intermediate apertures, and a pair of rollers within said drum and in frictional engagement with each other, whereby a rotation of one roller causes a rotation of the other roller in the opposite direction.
10. A fowl plucking device including a rotatable drum having its peripheral wall formed of spaced sections with intermediate apertures, and a pair of rollers within said drum and having frictional engagement with the inner surface of said peripheral wall.
- 40 11. A fowl plucking device including a rotatable drum having its peripheral wall formed of spaced sections with intermediate apertures, and a pair of rollers within said drum, said rollers being so mounted as to engage in succession with the successive sections of said wall during the rotation of the latter.
- 50 12. A fowl plucking device including a curved blade rotatable about the approximate center of curvature, and a pair of rollers disposed between said blade and said center, said rollers being positioned for frictional engagement with each other and for frictional engagement with the inner surface of said blade, whereby each roller rotates the other when the first mentioned roller is in engagement with said blade and the other roller is out of engagement therewith.
13. A fowl plucking device including a casing having an inlet opening, means for maintaining a suction within the casing to cause feathers to enter said opening, and a pair of rotatable members within the casing, one of said members being disposed within the other and having its center of rotation between the center and periphery of the outer member.
14. A fowl plucking device including a casing having an inlet opening, means for maintaining a suction within the casing to cause feathers to enter said opening, a curved blade within said casing and rotatable about the approximate center of curvature and having an edge movable past said opening, and means between said center of curvature and said edge for causing the feathers to bend about the edge of said blade during the rotation.
15. A fowl plucking device including a casing having an inlet opening, means for maintaining a suction within the casing to cause feathers to enter said opening, a curved blade within said casing and rotatable about the approximate center of curvature and having an edge movable past said opening, means between said center of curvature and said edge for causing the feathers to bend about the edge of said blade during the rotation, and means for varying the effective size of said opening.
16. A fowl plucking device including a casing having an inlet opening, means for maintaining a suction within the casing to cause feathers to enter said opening, a curved blade within said casing and rotatable about the approximate center of curvature and having an edge movable past said opening, means between said center of curvature and said edge for causing the feathers to bend about the edge of said blade during the rotation, and means for varying the effective size of said opening, said means being disposed at one side of the path of movement of said blade and movable toward and from said path.

Signed at New York, in the county of New York and State of New York this 11th day of February A. D. 1926.

AARON SIMONS.
